UNITED STATES PATENT OFFICE.

ARTHUR GRANDJEAN, OF SAN DIEGO, CALIFORNIA.

DUPLEX AIR-PUMP FOR CARBURETING OR GAS MACHINES AND THE LIKE.

1,279,859.

Specification of Letters Patent. Patented Sept. 24, 1918.

Application filed September 17, 1913. Serial No. 790,375.

To all whom it may concern:

Be it known that I, ARTHUR GRANDJEAN, a citizen of the United States, residing at San Diego, in the county of San Diego and 5 State of California, have invented a new and useful Duplex Air-Pump for Carbureting or Gas Machines and the like, of which the following is a specification.

This invention relates to an air pump for 10 apparatus applicable for use as a domestic gas machine in which hydrocarbons, such as gasolene, alcohol or other highly inflammable liquids are evaporated by air under pressure, for the purpose of supplying gas 15 pipes of lighting and heating systems with a combustible fluid that may be used at the gas burners of the system for both heating and lighting purposes.

An object of this invention is to provide 20 an air pump for apparatus of this character by which a uniform pressure of carbureted air will always be maintained at the burners without fluctuations and which will produce a practically permanent, uniform and stable burning fluid that is of the 25 nature of a dry gas not liable to lose its carbon by condensation while standing in the pipes during nonuse of the burners.

Further objects are maximum capacity, 30 minimum size, superior compactness, minimum number of parts, cheapness of manufacture, certainty of automatic action, and perfect regulation of fuel.

Other objects and advantages may appear 35 from the subjoined detail description.

The accompanying drawings illustrate the invention.

Figure 1 is a plan view of a carbureting apparatus employing a duplex pump, constructed in accordance with this invention, 40 the figure being partly in section on line x^1 , Fig. 2.

Fig. 2 is an elevation of the apparatus shown in Fig. 1, partly in mid-section and 45 viewed from the front of Fig. 1.

Fig. 3 is a vertical section of the air delivery valve on line x^3 , Figs. 1 and 4.

Fig. 4 is a section of the air delivery valve on line x^4 , Figs. 1 and 3.

50 Fig. 5 is a plan of one of the motor valves detached.

Fig. 6 is a vertical section of the motor valves in the axial plane of the valve stem on line x^6 , Figs. 1, 2, 5 and 7, the parts being in the position shown at the left in

Figs. 1 and 2. The valve stem and the valves are shown intact.

Fig. 7 is a mid-section on line x^7 , Fig. 1, 5 and 6.

In Figs. 5, 6 and 7, the parts are in the 60 position shown at the left in Figs. 1 and 2.

Arrows on the section lines indicate the direction of sight.

Like characters are applied to the same parts in the various views and where the 65 parts are duplicated distinguishing indexes are added to avoid confusion, but these are not invariably noticed in the verbal description.

In carrying out this invention provision 70 may be made for operating the air pumps by any motive power, as electricity or air or water under pressure, and in the accompanying drawings the apparatus will be shown as operated by water; that being sufficient for an understanding of this invention. 75

Each of the reciprocal bell type air pumps 1, 2, to supply air to the carbureter 3, comprises a tank 4, a bell element or receiver 80 5 working up and down, and each pump is provided with an air inlet 6 communicating with any suitable source of atmospheric air, an outlet 7 communicating (through means hereinafter described) with the carbureter 85 3, and a piston motor, comprising a vertical cylinder 8 fixed to the tank, and a piston 9 therein having a rod 10 connected to the bell 5 to raise said bell when water is admitted to the motor through the pipe 11 90 which is controlled by the over-balancing three-way motor valve 12.

In the drawings the elements pertaining to the air pumps, respectively, are marked with like reference characters, those applied to one air pump being distinguished by means of an index from those applied to the other air pump. 95

Between the air pumps 1, 2, there is provided the overbalancing air delivery valve 100 13 which has two inlets 14, 14'', and a single outlet through air pipe 15. The inlets are provided with valve seats 16, 16'' (see Figs. 3 and 4) that are respectively controlled by the valve plugs 17, 17'' which are 105 fixed to a valve stem 18 that is provided with two shoulders in the form of collars 19, 20 working in a cylinder 21 formed as the head of a T, in the stem 22 of which T is journaled transversely of the stem and head 110

of said **T** a rock-shaft 23, an arm 24 of which extends between the shoulders 19, 20, so that as the rock-shaft is operated the valve stem and the valves are shifted, first 5 in one and then in the other direction lengthwise of the **T**-head.

The stem 22 of the valve case forming **T** is provided with journal bearings 25, 26, formed integral therewith, one being blind 10 and supported by an external boss 27, and the other being formed in a threaded tubular projection on which is screwed a gland 28; there being packing 29 inside the gland and around the rock-shaft 23 to prevent 15 leakage.

Said rock-shaft 23 has a cylindrical portion inserted through the bearing 26 and through the rock-shaft arm 24 which is bored to receive it, and beyond said arm and 20 into the bearing 25. One or more set screws 30 screwed through the arm 24 serve to fix said arm on the rock-shaft and the projections 24" prevent endwise movements of the rock-shaft.

25 The valve case forming **T** stem 22 is connected by a union 32 with the air pipe 15 which leads upward to the carbureter through air delivery pipe 31, is provided with a check valve 33 and is connected with 30 the inlet 34 for gasolene or other hydrocarbon or other liquid fuel to be volatilized, and with the carbureter 3. The check valve 33 serves to prevent the return of the carbureted air from pipe 31 to the air in the air pipe 15 and also avoids the liability of any 35 escape of carbureted air from the apparatus in case the air supply valves 35 might leak. The valve 13 and the parts operating it constitute means to deliver air from the pumps 40 alternately into the air pipe.

The rock-shaft 23 is provided on its outer portion with an arm 36 adjustably fixed thereto by a set screw 37 and there is journaled on said rock-shaft a lever 38 which is 45 provided on opposite sides of the rock-shaft arm 36 with operating lugs 39, 39" and is also provided centrally with an over-balancing weight 40; and on opposite sides of the rock-shaft and weight with two arms 50 42, 42" to which are pivotally connected operating bars 43, 43" provided with buttons 44, 44" arranged to be pushed downwardly by the air delivery tappets 45, 45" that are carried by the weighted bells 5, 5". The 55 carbureter 3 receiving air from the air pipe 15 is connected by the carbureted air outlet pipe 46 leading from the top thereof, with a storage tank 47 from which the service pipe 48 leads.

60 The buttons 44, 44" are adjustably and yieldingly supported by means of springs *a* and set collars *b* so that they may be properly positioned on and will yieldingly slide along their bars, and in case the fluid that 65 operates either or both motors is shut off

and both bells descend at the same time the bells will be resiliently checked and will come to rest without jar.

Each bell is loaded with a weight *c* to force out the air with appropriate pressure. 70

The motor valves 12, 12" are alike and each comprises an **L** **T** and base formed integrally; the **L** member 49 being above and the base 50 being below the **T** proper. Said **L** member extends at right angles to the 75 barrel 51 of the **T**, is screw-threaded at its outer end and is provided with a bushing 52, which serves as a support for a rock-shaft 53 having an arm 54 at its inner end to extend between and act on valve shifting 80 lugs in the form of collars 55 that are fixed to the valve stem 56 which is provided at its ends with valve plugs 58 that alternately close valve seats 59 at the ends of the barrel 51 as the valve stem is shifted by said arm 85 54 of the rock-shaft.

The tubular stem 60 of the **L** **T** communicates with said barrel intermediate said valve seats 59 and also communicates with the motor cylinder 8 through pipe 11; and the open ends of the barrel communicate respectively with the supply and exhaust pipes 61, 62 for the water or other motive liquid to raise the bells. 90

A gland 63 is screwed onto the threaded end of the **L** limb of the **L** **T** and confines packing 64 therein to prevent leakage around the motor valve rock-shaft 53 which is provided with an arm 65 adjustably fixed on said rock-shaft by a set-screw 66; and a weighted lever 67 provided with side arms 68 and lugs 69 spaced apart to act alternately on the rock-shaft arm 65 is journaled on the rock-shaft, and is provided with an arm 70 having an over-balancing weight 701 and 100 extending in the same vertical plane with one of the side arms 68 and connected with the motor valve link 71 that slides through the tappet 72 which is fixed to the bell 5; said link having two buttons 73, 74 respectively above and below the tappet to shift the weighted arm from side to side of the rock-shaft, thus to operate the valve 12 to open the water supply port and close the 105 water exhaust port near the end of the descent of the bell and to close said supply port and open said exhaust port at the end of the ascent of the bell. 110

Each motor valve is operated by the bell to which its motor appertains at the close of both its rise and fall and the air valve is operated by the bells alternately and only at the close of the down motion thereof; the expiration of both pumps being controlled by operation of the respective pumps 115 alternately. 120

It is understood that it is not new to operate the valves of domestic gas machines by rods connected with the valves and having buttons acted on by a tappet carried by 130

the bell of an air pump and such an appliance is not broadly claimed herein.

It is to be noted, however, that although each motor valve is operated only by the bell driven by the motor which such valve controls, the air delivery valve is operated by both bells; the actuating movement occurring at the close only of the descent of each bell and being effective to close the air outlet from such descending bell and to open the air outlet from its mate, the other bell, to the air delivery pipe 15.

The motor push buttons 73, 74 on the motor valve links 71, 71" are arranged in such relation to the tappets 72, 72", respectively, and the air delivery push buttons 44, 44" on valve bars 43, 43", respectively, are located with such relation to the air delivery tappets 45, 45", respectively, and their bells 5, 5" and the other parts of the apparatus that the opening of the motor valve and the closing of the air valve for any air pump is effected while the bell of such pump is resting on the aerial contents of the pumps; and consequently the air pressure exerted by either bell on the air in the pump to which it pertains is not relieved until pressure is applied by its mate, the other bell, on the air in the other pump.

In this respect the buttons when depressed are mounted near the level at which the tappets come to rest when the bell is down and the length of the side arms 42, 42" and 70, 70" is sufficient to move the buttons from their depressed position below such level, up to a position above such level.

For convenience in describing the operation, bell 1 and the parts pertaining thereto may be termed the first bell and parts respectively; and bell 2 and its parts may be termed the second bell and parts respectively.

The practical operation of the air pumping portion of the apparatus may be understood by reference to Fig. 2 in which the first bell 5 is shown just beginning to descend and the second bell 5" is shown just beginning to rise.

This condition has been reached by the action just previously described of the tappets 45" and 72" upon the buttons respectively 44" and 74" which cause the overbalancing levers 38 and 67" with their respective weights 40 and 701" to operate the air delivery valve 13 and the motor valve 12" to open the way for air from bell 5 to air pipe 15 and for motive liquid from the service main through pipes 61" and 11" to drive the motor piston 9", thus lifting the bell 5" for inspiration of pump 2 during a period of the descent of bell 5 and until the tappet 72" lifts the button 73", thus bringing the overbalancing lever 67" and its weight 701" to overbalancing position, thus closing the passage from pipe 61" to pipe

11" and opening the passage from pipe 11" to the pipe 62", so that the bell 5" is free to descend except that the air delivery valve 13 is closed so that the air in pump 2 is confined under the pressure exerted by the bell 5". This is the relation in which the different parts of the apparatus remain during the further descent of bell 5 until the tappets 45 and 72 act upon the buttons 44 and 74 respectively, thereby operating the valves 13 and 12 to open a way for the air from bell 5" to air delivery pipe 15 and cutting off the way for the air from bell 5 to delivery pipe 15, and turning on water through pipes 61 and 11 to the motor 9 and cutting off the passage from pipe 11 to the exhaust pipe 62. By this action the air is allowed to flow from pump 2 to the carbureter and pump 1 is started on its inspiration which will continue in the manner just described for the inspiration of pump 2.

It is thus seen that there is constantly an air pressure maintained to force air through air delivery pipe 15 and so on to the carbureter and that the change from one pump to the other is practically instantaneous.

The air supply valve described herein is claimed in my copending application Serial No. 790,374, filed Sept. 17, 1913, patented Mar. 28, 1916, No. 1,177,100.

The exhaust water from the motor flows through the exhaust pipe 62 into the interior of the tank 4; said exhaust pipe there extending upward as a stand-pipe 75 to a level above the overflow port 76 which opens through the wall of tank 4, below the level of the mouths of the air supply and air delivery pipes. The overflow pipe 77 provided with the venting T 771 and leading to the drain pipe 78 is connected to the port 76, so that the water seal inside the tank and bell is replenished by the exhaust from the motor and is kept at a constant level below the tops of the pipes 6 and 7.

The washout valves 79, 79" open from the bottom of the tanks into the drain pipes 78 so that sediment deposits in the tanks can be drawn off.

The carbonaceous or other inflammable liquid which is to charge the pumped air is stored in the gasoline supply tank 80 and flows through gasoline supply pipe 81 to the carbureter pipe 31 through the gasoline supply valve 82 which is normally closed by pressure of lever 83 that is pivoted on the post 84 and on the valve stem 85 on which it is held down by suitable means as the weight 86. As a description of the means for opening the gasoline supply valve and holding it open for a determined period during each up stroke or inspiration of each pump, and also of the means for closing the valve is unnecessary for the understanding of the pump construction by any one skilled in the art, and as such means may be arranged in various

ways according to the judgment of the constructor, they are indicated in the drawings without having reference characters applied thereto, simply in order to show only in a general way how they may be connected with the pump structure.

By this means the attendant can adjust the apparatus to supply almost exactly the amount of liquid required to properly carburet the air so that the excess of liquid supplied to the air to produce a burning fluid or gas of the required richness will be minimized.

It is thus made possible to cause the air to absorb all the constituents necessary to produce a gaseous fuel high in B. T. U. and practically non-condensable under the conditions usually prevailing in the pipes and holders of lighting and heating systems.

20 The gasoline inlet 34 connects with the air delivery pipe 31.

The carbureter reservoir has a drain cock 112. The upper end of the equalizing pipe 109 leading from the bottoms of the carbureter communicates through a valve 113 and nipple 114 with the interior of the carbureter and also communicates across said valve 113 with the interior of the gasoline tank 80. The pipe 81 leads from the gasoline tank 30 through the valve 115.

The venting T 771 on the overflow pipe 77 allows the overflow from the tank 4 to flow out easily without obstruction from atmospheric pressure.

35 It is to be noted that the pumps are not united in operation but that each one operates to force the air through the carbureter to the storage tank independently of the other, that is to say, both pumps work independently of each other by the action of the water valve mechanism at each pump. By this apparatus or system the need of high gravity fuel is overcome as I am making gas by using fuel as low as 58° Baumé there-45 by making a safe gas for all purposes. By this system one air pump can operate alone and the other one remain at rest and when more gas is needed the three-way air valve is regulated or adjusted to operate both pumps.

50 I claim:—

1. The combination of tanks; bells in the tanks respectively; motors to raise the bells operable independently of each other respectively; means controlled by the bells respectively to turn on and off the motive power at the close of the descent and ascent of said bells respectively; valved air inlets for the bells respectively; air outlets for the bells respectively; an air pipe; a three-way 55 valve for alternately connecting the outlets with the air pipe; an air delivery pipe connected to the air pipe; a check valve between the air pipe and the air delivery pipe; and means operated by the movement of the bells to open one of the outlets and to close the other, and vice versa.

2. The combination of tanks; bells in the tanks respectively; motors to raise the bells operable independently of each other respectively; means controlled by the bells respectively to turn on and off the motive power at the close of the descent and ascent of said bells respectively; air outlets for the bells respectively; an air pipe; a three-way valve for alternately connecting the outlets with the air pipe; means operated by the descent of one of the bells to close its outlet and to open the outlet from the other bell; and means operated by the descent of the second bell to close its outlet and to open the outlet from the first bell.

3. Two air pumps of the bell type having bells that are operable independently of each other; motors to lift the pump bells respectively to cause inspiration of air thereto; an air pipe; a three-way valve connected with the air pipe and with the pumps; means operated by the bells alternately to operate the three-way valve and thereby control the expiration of air from such pipes; means operated by one of the air pumps to control the motor for such pump, and means operated by the second air pump to control the motor of the second air pump.

4. In a duplex air pump, the combination of two tanks, an independent piston motor in each tank, a water connection to each piston motor, bells in the tanks and connected to the piston motors, independent means for each bell whereby the water is turned on and off at the close of the descent and ascent of the bells, an air outlet for each bell, an air pipe, a three-way valve for alternately connecting the outlets with the air pipe, means operated by the descent of one of the bells to operate the three-way valve to close the outlet of that bell and open the outlet of the other bell, and means operated by the descent of the other bell to operate the three-way valve to close the outlet of the second bell and open the outlet of the first bell.

In testimony whereof I have hereunto set my hand at San Diego, California, this 10th day of Sept. 1913.

ARTHUR GRANDJEAN.
